UNITED STATES PATENT OFFICE.

BESSIE CUSTER, OF SATANTA, KANSAS.

UNION-GARMENT.

1,392,303.

Specification of Letters Patent. Patented Oct. 4, 1921.

Application filed October 22, 1918. Serial No. 259,222.

To all whom it may concern:

Be it known that I, BESSIE CUSTER, a citizen of the United States, residing at Satanta, in the county of Haskell and State of Kansas, have invented certain new and useful Improvements in Union-Garments, of which the following is a specification.

This invention relates to improvements in union garments of the type comprising shirt 10 and drawer portions.

One object of the invention is to provide a garment of this character in which the seat and crotch can be readily drawn up by the wearer so as to make a snug fit as may 15 be desired.

Another object is to provide a garment of this character having a seat flap provided with a single seam up the back made sufficiently long to permit ample room for sitting to render the garment comfortable.

Another object is to provide a garment of this character in which all of the adjustments made may be at the front and in an extremely easy manner.

With the foregoing and other objects in view, which will appear as the description proceeds, the invention resides in the combination and arrangement of parts and in the details of construction hereinafter described 25 and claimed, it being understood that changes in the precise embodiment of the invention herein disclosed may be made within the scope of what is claimed without departing from the spirit of the invention.

In the accompanying drawings:—

Figure 1 represents a front elevation of a garment constructed in accordance with this invention, the leg portions being broken off at their lower ends,

Fig. 2 is a side elevation thereof, and

Fig. 3 is a rear elevation.

In the embodiment illustrated a shirt portion 1 is shown and a drawer portion 2 made in one piece as is usual in garments of this character, the drawers having a seat flap 3 which is adapted to be dropped downwardly to uncover the seat opening.

The seat flap 3 is designed to extend up over the rear of the shirt portion 1 so that 50 a double thickness is formed at this portion of the garment, as is shown clearly in Figs. 2 and 3. The juncture of the flap 3 with the drawer portion 2 is reinforced as shown at 5 to prevent tearing at this point.

55 A belt 6 is secured to the upper edge of the flap 3 and is extended at its opposite

ends beyond the side edges of said flap and is preferably provided with elastic inserts 7 to render the garment comfortable, especially when used by old persons or by persons having large abdomens. The free ends 8 of the belt are provided with longitudinally spaced fasteners here shown in the form of buttonholes 9 formed in one end and buttons 10 carried by the other end. A 60 plurality of these fastening elements are provided so as to render the belt comfortable and to hold their ends in lapped relation.

Loops 11 are formed in alinement with the 70 under arm seams of the garment and at points adjacent the top of flap 3 and are designed to receive the belt ends so as to hold the flap against vertical movement when in adjusted operative position and to 75 operate as guides for the belt when the flap is being raised or lowered.

The belt loops are located at the sides of the garment in substantial alinement with the edge of the drop flap when in closed position. The invention herein permits the lowering and automatic retraction of the flap without disengaging the ends of the belt members from each other and retains 80 the flap in proper position.

The flap 3 has a single seam 12 up its center in alinement with the crotch of the garment and the length thereof permits ample room for the comfortable sitting of the wearer which is especially desirable for 85 a person riding in a saddle or sitting on hard chairs, the usual garment of this character having two seams.

The foregoing description and the drawing have reference to what may be considered the preferred or approved form of my invention. It is to be understood that I may make such changes in construction and arrangement and combination of parts, materials, dimensions, etc., as may prove expedient and fall within the scope of the claimed invention.

Having thus fully described my invention what I claim as new and desire to secure by Letters Patent, is:—

In a union garment, a drop flap provided with a pair of belt members at its upper ends adapted to extend around the front of the body of the wearer, said belt members provided with elastic sections, belt loops formed on the garment at the sides of the garment and in substantial alinement 100 110

with the upper edge of the drop flap when in closed position, said belt members passing through and being retained in position by said belt loops and means for adjustably connecting the ends of said belt members together whereby the circumference of said belt members may be increased or diminished, said elastic inserts in the belt permitting the drop seat to be lowered as de-

sired without disengaging the ends of the 10 belt members from each other.

In testimony whereof I affix my signature in presence of two witnesses.

BESSIE CUSTER.
